MEDULLARY PIN

Leslie V. Rush, Meridian, Miss.

Application February 15, 1949, Serial No. 76,552

6 Claims. (Cl. 128—92)

1

This invention relates to fracture fixing pins for the intramedullary fixation of fractures of the long bones.

Pins of the character stated are driven into the medullary cavity of a fractured bone to securely hold the fractured portions in firm contact while knitting, thereby reducing the necessity of immobilizing an injured extremity by casts, splints or other apparatus.

Applicant is aware that attempts have been made to employ pins driven longitudinally of a bone and traversing the area of fracture. However such pins as were heretofore devised have not been entirely satisfactory, particularly when entrance to the medullary cavity must be made through an oblique opening in the cortex. Under such circumstances, the pin has a tendency to penetrate the cortex on the opposite side of the bone and pass into the soft tissue.

An object of the present invention is to provide an improved pin of the character stated, which may be driven into the medullary canal and along the same from any indicated starting point and at various angles with minimal danger of penetrating or injuring the cortex beyond the initial point of entry.

A further object of the invention is to provide a pin as mentioned having means to prevent the pin from migrating into the bone while in use.

A further object of the invention is to provide a fixing pin formed with means whereby the pin may be axially rotated, when necessary, while being driven into position to maintain the pin in the desired path; and which will also serve as means to aid in extracting the pin after the fracture has healed.

Other objects will appear hereinafter.

In carrying out the present invention, the pin is preferably constructed of a rod having sufficient resiliency to adapt itself to the channel of the canal and to realign itself within the bone. The forward end of the pin is pointed, and curved to a more or less degree, with the outer face of the curved end presenting a sled-runner shaped surface which strikes the inner surface of the cortex and glides along the same thereby preventing the point from engaging and penetrating the cortex when the pin is properly driven into the bone with blows of a mallet.

The opposite end of the rod is bent upon itself forming a U-shaped or hooked head which makes it possible to drive the pin with a mallet without difficulty. The hooked end is preferably curved to the same side of the pin as that

2

to which the pointed end is bent, and engages the outside of the cortex when the pin is driven into place thereby preventing the pin from migrating into the medullary cavity or twisting while in use. When the pin is inserted in the bone, the hooked end projects a slight distance into the soft tissue and causes minimal irritation even in superficial locations, and is usually well tolerated by the tissues. Other functions of the hooked head will more fully appear hereinafter.

The invention will be more readily understood by reference to the accompanying drawings, forming a part of the specification and in which:

Figure 1 is a perspective view of a rack for holding a plurality of pins of graded lengths, and illustrating several pins supported therein.

Figure 2 is a side elevation of the headed end 20 of a pin embodying the invention.

Figure 3 is a rear elevation of the same.

Figures 4, 5 and 6 are front, side and rear elevations respectively of the forward or pointed end of the pin.

Figure 7 is an end view of the pin.

Figure 8 is a longitudinal sectional view of a humerus drilled at the upper end to admit a pin into the medullary cavity.

Figures 9, 10 and 11 are similar views of the 30 humerus illustrating successive stages, respectively, in the process of inserting a pin therein.

Figure 12 is a longitudinal sectional view of a fractured femur with a fixing pin inserted therein.

Figure 13 is a similar view of a fractured 35 femur in which the fracture is located toward the lower end, and illustrating the use of two pins to maintain the parts in fixed position.

Figure 14 is a detail section illustrating the manner of attaching a fractured condyle to the humerus.

Figure 15 is a longitudinal section of a fractured clavicle with a fixing pin inserted therein.

Figure 16 is a diagram of a hand and wrist, 45 illustrating a fractured radius and a fractured metacarpal bone, each with its parts held in place by a pin.

Referring to the drawings 10 indicates the pin which is formed of a round stainless steel rod, preferably 18-12 stainless steel, which can be purchased in rods of suitable diameters. Such rods adapt themselves well to fashioning, and when hardened, have sufficient strength for the purpose intended; and also are corrosion resistant and non-magnetic.

However the invention is not limited to the use of any particular metal, alloy, or other material, provided it is corrosion resistant, and has sufficient strength and resiliency to meet the necessary requirements.

The rod 10 is slightly bent near one end, as at 11, and then bent upon itself forming a hooked or U-shaped head 12 which is offset from the axis of the pin and adapted to receive the blows of a mallet. The end 13 of the U-shaped head 10 is rounded and smoothed as by grinding and terminates in a tip 14 which is preferably obtusely sharpened.

The forward or opposite end 15 of the rod from the head 12 is slightly bent or curved toward the same side as said head, and the outer curve thereof is ground to form a sled-runner shaped face 16. Upon each side of said face 16, the end 15 is ground obliquely backwardly, as at 17, forming a tapered point 18 to afford better penetration.

While only a slight curve or bend to the forward end of the pin is preferably provided when the pins are formed, the surgeon may vary the curvature of the point as indicated by the particular case. When the pin may be inserted at the end of a bone or at only a slight angle to the axis of the bone, the normal slight curvature is sufficient; but the more oblique the entry must be made to the axis of the bone, the greater the curvature that must be given the pointed end in order that the face 16 shall engage and ride upon the cortex instead of the point 18. This extra curvature may be given to the point by the surgeon in the operating room after the angle of entry has been determined.

Since the use of the pin may be adapted to most of the long bones of the body, it becomes necessary for the surgeon to have available a large assortment of pins, varying both in diameter and in length. In practice it is desirable to furnish the pin in sets of $4/16''$ diameter which are used for the femur; $3/16''$ diameter for the humerus and tibia, $2/16''$ for the radius, ulna and fibula, and smaller ones for the clavicle, metacarpal and other small bones.

It can be determined in advance of an operation the suitable diameter of pin to be used for a given bone, but the length thereof must be carefully chosen for the individual patient. It is therefore necessary to provide the pins of each diameter, in sets varying in lengths by fractions of inches. It is also well to provide a separate rack for each diameter of pin and so arranged as to accommodate a set of pins of that particular diameter but of the varying lengths.

Any desired form of rack may be employed, but the type illustrated in Figure 1 of the drawings is convenient. As shown herein, the rack comprises a plate 21 from which extend upper and lower flanges 22 and 23 respectively each provided with a number of perforations 24 to receive the pins 10 as illustrated; the hooks 12 resting upon the upper flange 12 and thereby supporting the pins in the rack. Preferably, the indicia 25 are provided adjacent the position provided for each pin of a given length, so that they may be readily selected. It is also obvious that with a rack of the type disclosed, the full set of pins may be readily sterilized without removal from the rack.

In Figures 8 to 11 inclusive, is illustrated the method of inserting the fixing pin 10 in a fractured humerus. The shaft *a* of the humerus includes the cortex *b*, and the medullary cavity *c*

containing the marrow. The pin is entered through the superior surface of the tuberosity *d*, a drill hole *e* being preferably provided for the entrance, although the pin may, if desired, be driven into the bone without drilling. The direction of the pin through the tuberosity is preferably at a slight angle to the axis of the shaft *a* so that the sled-runner shaped face 16 will engage the cortex *b* and be deflected downwardly, thereby preventing the tip of the point 18 from entering or perforating the cortex. The face 16 follows down the surface of the cortex and thus serves to guide the pin. As the cavities of bones vary somewhat it is not unusual to see the pin rotate somewhat as it is driven down the shaft; and it sometimes becomes necessary to rotate the pin manually into its proper relation. It is obvious that this may be readily done by means of the hooked head 12. The pin is driven downward to a point just above the olecranon fossa, a pin of the proper length having been selected; and the point 14 of the head engages the bone and holds the pin firmly against any tendency to twist.

Figure 12 illustrates a femur *f* fixed with a pin 10. When the fracture of the femur is in the upper two-thirds of the shaft, as indicated in this figure, the pin is introduced through the superior portion of the great trochanter *g*, and driven downwardly to the supracondylar region. When the fracture occurs in the lower third of the shaft of the femur, the medullary canal is so spacious that a good fixation is best had by introducing a pin through the medial epicondyle *h* and driving the pin upwardly as illustrated in Figure 13. In such cases the use of two pins, as shown, is usually indicated.

Figure 14 illustrates the manner of attaching a fractured condyle *i* to the humerus at the elbow.

In Figure 15, *j* indicates a fractured clavicle in which the pin 10 is inserted through an oblique drill hole *e* in the cortex.

In Figure 16, *k* indicates a fractured metacarpal bone with a small pin 10 inserted therein and *l* indicates a fractured radius with the pin 10 therein.

It should be noted that in every use of the fixing pins, only the rounded head 12 extends into the soft tissues adjacent the bone, and this is not likely to cause irritation even in superficial locations.

When the pin has served its purpose it may be removed. In superficial locations the head of the pin may be palpated through the skin and the pin removed through a small incision under local analgesia. To remove the pin after the head 12 has been exposed, it is necessary only to engage the tip of a screw driver within the hooked head and tap the same with a mallet.

It should also be understood, in connection with the mounting and removal of my improved fracture fixing pins that the hooked end thereof may, when desired, be bent at a right angle to the point, or in fact in other selected directions according to the particular place of insertion and the will of the surgeon.

When using fixing pins as above described it is rarely necessary to supplement them with casts, external splints or other apparatus, so that the injured member is not immobilized, and the patient is more quickly able to use the injured part. Also it has been found that the healing of the fractured bone is more rapid than when immobilized.

It is believed the herein disclosed fracture fix-

ing pin is the only one which utilizes the spring principle of three-point pressure, utilizing the resiliency inherent in the pin and the natural pull of the muscles in the extremity. For example, in the fixation of a fracture of the femur, as illustrated in Figure 12, the strong pull of the adductor muscles which will be recognized as upward and to the left from the lower end portion of the femur toward the pelvis with which the femur would be connected give the fractured femur a tendency to bow in an antero-lateral direction or toward the left as viewed in Figure 12. The fixing pin, being curved as indicated in Figure 12 utilizes this muscle pull by its tendency to bow medially, resulting in three-point pressure, centrally and at each end, resulting in more secure fixation without the necessity of impacting the marrow cavity. This same principle, while varying with the muscle pull in various parts of the body, is an important factor in secure fixation of many of the long bones, particularly with reference to preventing rotation.

It is to be understood that the herein disclosed pin does not fill the medullary canal, thereby allowing the bone to be free to glide upon the pin, so that the ends of the bones are in constant contact, allowing the normal muscle pull of the extremity to continuously compress the bone ends to stimulate osteogenesis or bone healing.

Again with reference to the benefits of the resiliency inherent in the disclosed fracture fixing pins attention is directed to Figure 14 wherein the fracture of a humerus condyle is shown. In a fracture of a condyle or bony prominence near a joint, the tendency of the fragment is to displace laterally, or to the right as viewed in Figure 14. By bending the pin slightly near its point and leaving the head or hook end straight, the pin will travel in an arc through the cancellous bone until its arc flattened end portion strikes the cortex of the shaft. This causes the pin to continue travelling in an arc, and as the straight head end part of the pin is forced to travel this same arc it results in a spring force which compresses the broken fragment toward the left or toward the midline.

While one form of the invention has been shown for purposes of illustration, it is to be clearly understood that various changes in the details of construction and arrangement of parts may be made without departing from the spirit and scope of the invention as defined in the appended claims.

I claim:

1. A fracture fixing pin comprising a flexible rod of generally circular cross section having a smooth exterior and a pointed entry end, and a curved guiding face at one side adjacent said pointed end and so placed with relation to the point as to be engageable with the cortex at the side remote from the point of entry of the pin when driven into a medullary canal at an angle to the axis of the canal and act to deflect said point in a manner for preventing penetration of said cortex by said point.

2. A fracture fixing pin as defined in claim 1 in which the pointed end is longitudinally curved slightly and the outer arc of said pointed end curve bears the guiding face, said face being approximately flat in transverse section and tapered at opposite side edges of the point.

3. A fracture fixing pin as defined in claim 1 in which the pointed end is longitudinally curved slightly and the outer arc of said pointed end curve bears the guiding face, said face being approximately flat in transverse section and tapered at opposite side edges to the point, and said end being acutely bevelled transversely of the rod at said side edges and merging into said point.

4. A fracture fixing pin as defined in claim 1 in which the rod end remote from the point terminates in a hook bending away from the side remote from the side having the curved guiding face, said hook merging smoothly with the main body of the rod at its full cross section and gradually reducing in cross section into a point disposed for engagement in bone adjacent the point of entry of the pin in a manner tending to secure the pin against migration.

5. A fracture fixing pin comprising a rod smooth of external surface and round in cross section and having a pointed entry end with the point disposed to one side of the axis of the rod, and a single flat guiding face merging into said point from the opposite side of the rod, and having at its other end a retraction facilitating hook portion bearing a predetermined definite relation to said flat guiding face, said pin while being pliable to an extent for permitting preset shaping prior to insertion and during driving also having inherent resiliency effective to cause it constantly to tend to return to its present shape during its active positioning in a fractured bone structure.

6. A fracture fixing pin comprising a longitudinal rod smooth of external surface and generally round in cross section along its main body and having an entry end presenting a single relatively flat guide surface adapted to facilitate travel along a medullary canal and transversing the axis of the main body at an angle across the full width of said main body and having at its other end a driving and retraction facilitating head offset in a predetermined definite direction with relation to said flat guide surface and adapted to remain close outside of and close against a bone as a migration stop and bent back upon itself in the direction of the length of the main body of the rod and shaped to present a well rounded smooth surface which minimizes irritation of overlying tissues and which starts at the full cross section of the main body at its juncture with said main body and gradually merges into a terminal point.
